UNITED STATES PATENT OFFICE.

THOMAS W. FELTON, OF SAN GABRIEL, TEXAS.

RAIL TIE AND FASTENER.

1,275,544.

Specification of Letters Patent. Patented Aug. 13, 1918.

Application filed February 18, 1918. Serial No. 217,836.

To all whom it may concern:

Be it known that I, THOMAS W. FELTON, a citizen of the United States, residing at San Gabriel, in the county of Milam and 5 State of Texas, have invented certain new and useful Improvements in Rail Ties and Fasteners, of which the following is a specification.

The present invention relates to rail-road 10 ties and rail fasteners, and aims to provide a novel and improved rail-tie and fastener which will support and hold the rails in a substantial manner and prevent displacement and spreading thereof, so as to avoid 15 wrecks or accidents and consequent loss of lives and property.

The invention has for its object the provision of a rail-road tie of novel construction to accommodate and brace the rails in a most 20 effective manner, and permit the parts to be easily put together and taken apart without requiring skilled labor.

With the foregoing and other objects in view, which will be apparent as the nature 25 of the invention is better understood, the invention resides in the construction and arrangement of parts hereinafter described and claimed, it being understood that changes can be made within the scope of 30 what is claimed without departing from the spirit of the invention.

The invention is illustrated in the accompanying drawing, wherein—

Figure 1 is the elevation of the tie, portions being shown in section.

Fig. 2 is an enlarged plan view of one end portion of the tie.

Fig. 3 is a perspective view of one of the removable inner rail braces.

The rail-tie proper is designated 4 and is constructed of iron, steel or other suitable material, so that it will be durable and strong. The end portions of the tie are offset downwardly, as at 5, and are provided with transverse depressions or channels 6 for snugly receiving the bases of the rails R which seat on said end portions 5, the walls of said depressions forming the shoulders 7 against which the outer edges 50 of the rail bases abut, and the shoulders 8 against which the inner edges of the rail bases abut. The inner shoulders or abutments 8 are spaced from the upper shoulders 9 of the tie 4 formed by the offsetting of 55 the end portions thereof.

The portions 5 have integral therewith the upstanding outer rail braces 10 offset inwardly to overlap the outer flanges of the rail bases and bear against the webs of the rails underneath the heads thereof. The inward offsetting of the braces 10 gives them the ledges 11, and the rails in bearing outwardly against the braces 10 will be prevented from spreading or tilting outwardly.

Removable inner braces 12 are used at 65 the inner sides of the rails to brace them from the inside, and these braces decrease in thickness from their rail engaging portions to their opposite edges 13 which are preferably rounded to seat against the shoulders 9. Said shoulders 9 are undercut or grooved to receive the edges 13 of the braces 12, and permit said braces to be swung upwardly and downwardly, and the undercutting or grooving of the shoulders 9 75 provides the overhanging lips 14 for holding the edges 13 down on the tie. The braces 12 are shaped to overlap and fit on the inner flanges of the rail bases and have the lower shoulders 15 to abut the inner 80 edges of the rail bases above and coinciding with the shoulders or abutments 8. Each brace 12 is provided at its ends with lugs 16 projecting away from the corresponding rail at an angle with and beyond the fulcrum edge 13, to overlap the tie 4 at the opposite sides thereof behind the shoulders 9, and thus prevent the lateral displacement or 85 sliding of the brace 12 on the tie.

In applying the brace 12, the edge 13 90 thereof is seated on the respective end portion 5 of the tie and then shifted against the shoulder 9 under the lip 14, the lugs 16 overlapping the sides of the tie. The rail engaging portion of the brace 12 is swung 95 downwardly, in the direction of the arrow in Fig. 1, to bring it under the head of the rail against the web and on the inner base flange. The brace 12 swings on the edge 13 as a fulcrum, and said edge is held down by the lip 14 which overlaps or overhangs it. The shoulder 9 also holds the brace 12 against movement away from the rail and the brace 12 will in fact drop into place of itself when set on the tie with its edge 13 near the shoulder.

The braces 10 and 12 are provided with transverse openings 17 for the reception of bolts 18 that are inserted therethrough and through holes in the rails, for clamping the 110

rails between the braces. The openings or apertures 17 and bolts 18 are located above the ledges 11, and washers 19 are disposed between the heads and nuts of the bolts and the braces, and are shaped to fit the inclined surfaces of said braces. After the braces 12 are applied, the bolts can be readily inserted and tightened, whereby the rails are fastened to and supported by the tie in a substantial manner. By removing the bolts, the braces 12 can be readily swung upwardly and removed, for making repairs.

Having thus described the invention, what is claimed as new is:—

15 1. A rail tie having an outer rail brace, and an inner shoulder, and a removable inner rail brace having a fulcrum edge to seat against said shoulder and means engageable with the tie to prevent displacement of said inner rail brace.

20 2. A rail tie having an outer rail brace,

Copies of this patent may be obtained for five cents each, by addressing the "Commissioner of Patents, Washington, D. C."

and an inner undercut shoulder, and a removable inner rail brace having a fulcrum edge to fit said shoulder and swing against the rail, and having lugs to overlap the tie 25 and prevent sliding.

3. A rail tie having a pair of braces for clamping a rail therebetween, one being swingable downwardly and having an inclined face, and securing means extending 30 through the braces and engaging said face.

4. A rail tie having a brace, a shoulder and a seat for the rail therebetween, a second brace having a fulcrum edge to seat against said shoulder and swing toward the 35 first named brace and seat for clamping a rail, the second named brace having an inclined face, and securing means extending through the braces and bearing against said inclined face.

THOS. W. FELTON.
